COMBINED BAFFLE AND GRILLE FOR A LOUDSPEAKER

Aston L. Moore, 220 Hammond Place,
South Bend, Ind. 46601

Filed Dec. 4, 1967, Ser. No. 9,630

Term of patent 14 years

(Cl. D26—14)

Fig. 1

Fig. 3

Fig. 2

FIG. 4

FIG. 5

FIG. 6

FIGURE 1 is a top perspective view of a combined baffle and grille for a loudspeaker showing my new design;

FIGURE 2 is a bottom plan view thereof;

FIGURE 3 is a sectional view thereof taken along the line III—III in FIGURE 2;

FIGURE 4 is a top plan view of a modified embodiment of the design illustrated in FIGURE 1;

FIGURE 5 is a bottom plan view thereof;

FIGURE 6 is a sectional view thereof taken along the line VI—VI in FIGURE 5;

FIGURE 7 is a top plan view of a further modified embodiment of the design illustrated in FIGURE 1;

FIGURE 8 is a bottom plan view thereof; and

FIGURE 9 is a sectional view thereof taken along the line IX—IX in FIGURE 7.

I claim:

The ornamental design for a combined baffle and grille for a loudspeaker, as shown and described.
